UNITED STATES PATENT OFFICE.

FRANK F. ROWELL, OF SCRANTON, PENNSYLVANIA.

URINAL-SLAB.

963,472.

Specification of Letters Patent. Patented July 5, 1910.

Application filed June 8, 1909. Serial No. 499,925.

To all whom it may concern:

Be it known that I, FRANK F. ROWELL, a citizen of the United States, residing at Scranton, in the county of Lackawanna and 5 State of Pennsylvania, have invented certain new and useful Improvements in Urinal-Slabs, of which the following is a specification.

My invention relates to urinals and particularly to a floor slab therefor adapted to be used either alone as a urinal or in conjunction with a back slab or with any other type of urinal.

In urinals as ordinarily constructed, the 10 urinary droppings fall upon the floor beneath the urinal and thus a very unsanitary condition arises.

Urinals have been constructed in which a floor slab is to be used, but in these the floor slab is made with an unbroken upper surface which is unflushed and therefore is in many ways as bad from a sanitary point of view as a urinal without any floor slab would be.

25 In order to avoid the above recited objections, I have provided a floor slab consisting of a body of china, porcelain, cement, or other suitable material, the upper surface of which at its forward end is formed 30 with a series of ribs or corrugations upon which the user stands. The rear of the slab is sunken and provided with an outlet, and in conjunction with the series of ribs I provide means for flushing the grooves between 35 the ribs. In conjunction with a floor slab as above constructed, I may also provide a ventilating hood located near the floor of the slab but at its rear end and adapted to carry off all foul odors. Further, the floor 40 slab is so constructed that it may be applied in connection with a back slab having the usual flushing arrangements.

45 Referring to the drawings: Figure 1 is a perspective view of my improved floor slab used in conjunction with a back slab. Fig. 2 is a longitudinal vertical section of Fig. 1. Fig. 3 is a plan view of a modified form of floor slab. Fig. 4 is a longitudinal vertical section on the line 4—4. Fig. 5 is 50 a fragmentary transverse section on the line 5—5 of Fig. 3.

55 My slab consists of a base 2, which may be made of vitreous china, glazed or unglazed, porcelain, fire-clay, cement, or any suitable or desirable material. At its rear the slab is provided with an upwardly extending

flange 3, the upper edge of this flange being rabbeted, as at 4, to form a joint with the back slab. The rear is also provided with the forwardly projecting side flanges 3^a, 60 which are also rabbeted to form a joint with the side flanges of a back slab. Both sides of the slab are provided with the marginal upwardly extending flanges 5. The upper surface of the slab is inclined downwardly 65 from front to rear so as to drain toward the rear of the slab. The front wall 7 is tubular, as shown at 8, and extending from this wall toward the rear of the slab, are a series of ribs and grooves 9. These extend rearwardly a sufficient distance to give a proper tread surface of sufficient length for a person to stand thereon. The floor of the slab at the rear has the opening 10, which may be fitted with a drain pipe and strainer or 70 any other means for carrying off the liquid material at the lowest level of the slab.

75 The tubular bore 8 has a series of holes 11 opening into spaces between the ribs 9. This tubular bore is adapted to be connected to any source of water supply and to this end may be provided with an internal tubular lining 11^a provided with holes which will align with the holes in the wall 7, this being connected to a water supply pipe. 85

80 While the floor slab as above described may be used by itself as a urinal, I may also provide in conjunction therewith, the back slab 12 having the side walls 13. The side walls and back slab are rabbeted, as before referred to, having engagement with the rabbeted flanges of the base. The upper 85 end of the back slab is provided with any suitable constant or intermittent flushing device whereby streams of water may be directed down the face of the back slab and drained off through the outlet 10 of the floor slab. 14 designates a water inlet pipe for this purpose and 15 a tubular header by which the water is directed along the face of 100 the slab, this header being perforated. The bore 8 may also be connected to any constant or intermittent source of water supply so that the floor slab may be flushed intermittently or continuously. 105

110 Preferably, the floor slab at its rear end is provided with a hood 16 which is formed integrally with the rear flange 3 and projects outwardly and downwardly over the outlet 10, the hood 16 projecting out far enough so that water passing down the back slab will be carried out to a point where it

will drip immediately into the drainage recess 17 which surrounds the outlet pipe. The back flange 3 is perforated as at 18 and connected with any suitable vent pipe or 5 other outlet for foul odors. While I have shown the hood as semi-circular in plan, I do not wish to be limited to this special form.

It is designed that this floor slab may be used in conjunction with any type of water 10 flushing urinal desired, but, as before stated, the slab may be used by itself as a urinal or a number of these slabs may be placed together to make a continuous urinal of any extent desired.

15 The advantages of my invention reside in the fact that a floor space is provided having a minimum of tread surface, thus permitting the urinary droppings to be carried forward and drained into the outlet pipe 20 and preventing the face of the slab from remaining in any wet condition. Further than this, my construction permits of flushing beneath the feet of the users, thus cleansing points of contact, neutralizing the uric 25 acids, and eliminating all odors arising from urinary droppings. Further than this, my construction provides a sanitary floor base for the ordinary form of back slabs, which may be used either by itself or in conjunction 30 with any form of back slab, and which being a unit, may be conjoined with other like units to form a urinal of any desired length. In addition to these advantages, the ventilating hood carries off foul odors at 35 the point where they are particularly generated.

My invention is simple, sanitary, easily made, and has been found extremely effective in practice.

40 Having thus described the invention, what I claim as new is:

1. A urinal floor slab consisting of a base having at one end a drainage opening, and having its upper surface inclined toward the 45 drainage opening, said upper surface having a series of ribs directed toward the drainage opening and forming a tread surface, the higher end of the slab being provided with a water chamber adapted to be 50 connected to a source of water supply, said chamber having perforations leading therefrom to the spaces between the ribs, said ribs having a rounded upper edge.

2. A floor slab for urinals comprising a 55 base having a rearwardly and downwardly inclined upper surface, a transverse gutter at the rear of the base inclined toward the middle of the rear of the base, the slab

being provided at this point with a drainage opening, said upper surface of the slab 60 having thereon a series of ribs directed toward the said gutter and drainage opening and forming a tread surface, the upper edges of the ribs being rounded, the higher end of the slab being provided with a water 65 chamber extending across the ends of all the ribs and connected to a source of water supply, said chamber having perforations leading therefrom to the spaces between the ribs.

3. A floor slab for urinals comprising a 70 base having an up-standing marginal flange, the rear flange of the base having a rounded inside face, said base having inside of said flange a rearwardly and downwardly inclined upper surface provided at its lowest 75 point with a drainage opening, the face of the base being formed with a series of ribs extending directly toward the lowest portion of the base, said ribs being rounded upon their upper edges, the end flange of 80 the base opposed to the drainage opening being tubular and provided with means whereby it may be connected to a source of water and being further provided with perforations alining with the spaces between 85 the ribs and adapted to direct flushing water into the spaces between the ribs.

4. A combined urinal stall and floor having an inlet pipe and a series of small outlet nozzles formed in the back of the stall 90 and arranged to flush the back and sides of the stall and another pipe opening upon the floor and having a series of small nozzles arranged to thoroughly flush the floor, said floor being inclined downward and rearward and there provided with a drainage outlet, said floor being further provided with a series of rearwardly extending upwardly projecting ribs forming a tread surface, said ribs being rounded upon their 95 upper edges.

5. In a urinal, a rear wall and a floor, said floor being rearwardly inclined and provided with a drainage outlet, the rear wall having a flushing inlet and the front 100 end of the floor being also provided with a flushing inlet, said floor being formed with a series of integrant ribs forming a tread surface and extending across the rear wall.

In testimony whereof I affix my signature 110 in presence of two witnesses.

FRANK F. ROWELL. [L.S.]
